DISCONNECTING CONTACT

Benjamin I. Hayford, Forest Hills, Pa., assignor
to Westinghouse Electric & Manufacturing
Company, East Pittsburgh, Pa., a corporation
of Pennsylvania

Application May 14, 1941, Serial No. 393,342

5 Claims. (Cl. 173—363)

My invention relates, generally, to electric switches and, more particularly, to the disconnecting contact members of electric switches suitable for disconnecting removable circuit breakers from the current conductors of a power system.

The conventional disconnecting contact assembly for metal clad switchgear, as manufactured at the present time by the manufacturers of switchgear apparatus, utilizes circular or garter springs wrapped around the contact segments or fingers to exert radial contact pressure. With springs of this type there is a possibility of one of them breaking and, when straightened out, being of sufficient length to ground the circuit breaker or the bus.

An object of my invention, generally stated, is to provide a disconnecting contact which shall be simple and efficient in operation and which may be economically manufactured and installed.

A more specific object of my invention is to provide a disconnecting contact suitable for connecting round current conducting members.

Another object of my invention is to provide for utilizing flat springs to apply radial pressure to the contact fingers of a disconnecting contact of the circular type.

A further object of my invention is to enclose the contact members of a circular disconnecting contact.

Other objects of my invention will be explained hereinafter or will be apparent to those skilled in the art.

According to my invention, the contact members of a disconnecting contact of the circular type are enclosed by a cylindrical sleeve which also functions to maintain the contact fingers in spaced relation. A flat spring is disposed between each of the contact fingers and the sleeve to provide contact pressure between the contact fingers and the round studs or conductors which are bridged by the contact fingers.

For a fuller understanding of the nature and objects of my invention, reference may be had to the following detailed description, taken in conjunction with the accompanying drawing, in which:

Figure 1 is a view, partially in section and partially in elevation, of a disconnecting contact embodying my invention;

Fig. 2 is a sectional view, taken along the line II—II of Fig. 1; and

Fig. 3 is a view, in perspective, of one of the contact fingers and its cooperating spring member.

Referring to the drawing, and particularly to Fig. 1, the disconnecting contact shown therein is comprised of two parts, a moving contact 10 and a stationary contact 11. The stationary contact 11 may comprise a round stud 12 which is mounted in a porcelain bushing 13. The stud 12 is provided with a shoulder 14 which is disposed on one side of a partition 15 in the bushing 13 and a nut 16 which may be screwed up against the other side of the partition 15, thereby securely fastening the stud 12 in the bushing 13.

The moving contact 10 may comprise a stud 17 which may be part of a circuit breaker structure (not shown) and a plurality of contact fingers 18 disposed around the periphery of the stud 17. The contact fingers 18 are enclosed by a sleeve 19, which is preferably composed of steel or other suitable material.

As shown in Fig. 3, an individual spring 20 is provided for each one of the contact fingers 18. Each end of the spring 20 is slotted and portions 21 of the spring are bent over to engage the sides of the contact finger, thereby retaining the finger and the spring in assembled relation. As shown in Fig. 1, the metal sleeve 19 is provided with an inwardly extending projection 22 which has notches 23 for receiving the springs 20, thereby maintaining the contact fingers 18 in spaced relation around the periphery of the stud 17. In this manner the springs 20 function to maintain contact pressure between the fingers 18 and the studs 12 and 17, as well as to retain the contact fingers in spaced relation.

A groove 24 is provided in the stud 17 for receiving an inwardly extending projection 25 on each of the contact fingers 18, thereby retaining the fingers on the stud 17 when the moving contact 10 is disengaged from the stationary contact 11. It will be noted that the groove 24 is slightly wider than the projection 25 on the contact fingers 18. In this manner a predetermined amount of longitudinal movement of the contact fingers 18 with respect to the stud 17 is permitted, thereby providing a wiping action between the contact fingers 18 and the stud 17. However, the longitudinal movement is limited by the groove 24 and the projection 25.

In order to prevent collapsing of the contact fingers 18 when they are disengaged from the stud 12, the sleeve 19 is provided with an inwardly extending flange 26 which is disposed to engage an extension 27 on each of the springs 20. As explained hereinbefore, the portions 21 of the springs 20 firmly grip the contact fingers 18. In

this manner the radial movement of the contact fingers is limited by the flange 26 on the sleeve 19 and the extension 27 on the spring 20, and collapsing of the contact fingers is prevented.

From the foregoing description it is apparent that I have provided a disconnecting contact assembly which is full floating and permits relative misalignment between the moving contact 10 and the stationary contact 11. Furthermore, the use of flexible shunts in the contact structure is entirely avoided since the current is conducted between the studs 12 and 17 by the bridging contact members 18 which are of a rigid construction. I have also eliminated the use of circular or garter springs which, as explained hereinbefore, may cause serious trouble in the event of breakage of one of the springs. The enclosing sleeve herein described not only cooperates with the flat springs to maintain the desired contact pressure, but also affords protection for the current conducting parts of the contact assembly.

Since numerous changes may be made in the above described construction and different embodiments of the invention may be made without departing from the spirit and scope thereof, it is intended that all matter contained in the foregoing description or shown in the accompanying drawing shall be interpreted as illustrative and not in a limiting sense.

I claim as my invention:

1. A disconnecting contact comprising, a round stud, a plurality of contact fingers disposed around the periphery of and supported by said stud, means on the stud cooperating with means on the fingers for limiting longitudinal movement of the fingers, a tubular sleeve surrounding the fingers, means on said sleeve for retaining the fingers in spaced relation, resilient means disposed between said sleeve and said fingers for maintaining contact pressure between the stud and the fingers, and extensions on said resilient means for engaging opposite sides of said fingers to retain them in the sleeve.

2. A disconnecting contact comprising, a round stud, a plurality of contact fingers disposed around the periphery of said stud, means on the

stud cooperating with means on the fingers for limiting longitudinal movement of the fingers, a cylindrical sleeve surrounding the fingers, internally projecting means on said sleeve for retaining the fingers in spaced relation, and a spring disposed between each of said fingers and the internally projecting means on said sleeve for maintaining contact pressure between the stud and the fingers.

3. A disconnecting contact comprising, a round stud, a plurality of rigid contact fingers disposed around the periphery of and supported by said stud, a tubular sleeve surrounding the fingers, an individual spring for each contact finger disposed between the finger and the sleeve for maintaining contact pressure between the stud and the finger, means on said springs for engaging said fingers, and means on said sleeve engaging said springs to retain the fingers in spaced relation.

4. A disconnecting contact comprising, a round stud, a plurality of rigid contact fingers disposed around the periphery of said stud, a cylindrical sleeve surrounding the fingers, an individual spring for each contact finger disposed between the finger and the sleeve for maintaining contact pressure between the stud and the finger, and means on said springs for engaging said fingers to retain them in spaced relation, said springs being disposed in notches provided on the inner surface of said sleeve.

5. A disconnecting contact comprising, a round stud, a plurality of rigid contact fingers disposed around the periphery of and supported by said stud, a cylindrical sleeve surrounding the fingers, an individual spring for each contact finger disposed between the finger and the sleeve for maintaining contact pressure between the stud and the finger, means on said springs for engaging said fingers, and means on said sleeve engaging said springs to retain the fingers in spaced relation, said sleeve having an internal flange disposed to engage one end of said springs to limit the radial movement of said fingers.

BENJAMIN I. HAYFORD.
